UNITED STATES PATENT OFFICE.

EMIL HAEFELY, OF BASEL, SWITZERLAND.

APPARATUS FOR THE MANUFACTURE OF MICA-COATED FIBROUS MATERIAL.

Application filed July 12, 1924, Serial No. 725,723, and in Switzerland July 28, 1923.

This invention relates to an apparatus for the manufacture of mica-coated fibrous material for electric insulating purposes by automatically cementing small sheets or 5 scales of mica on to a web of fibrous material, and has for its object to provide an improved simple apparatus for this purpose.

The improved apparatus comprises means for covering a conveyor band with the mica 10 scales and means for transferring the latter from the conveyor band to the fibrous material by a pressing action with the assistance of an agglutinant. The apparatus operates in such a way that an endless conveyor band running over guides, is covered 15 with mica scales and is brought into engagement with a band or strip of fibrous material, and together with this band or strip and with an agglutinant is conveyed to the 20 active region of a heated pressure roller, so that the sheets or scales of mica are, by means of the pressure exerted by this roller, transferred from the conveyor band with the aid of the agglutinant to the web of 25 fibrous material.

The invention is illustrated by way of example in the accompanying drawing, the single figure of which is a view in side elevation of one form of apparatus embodying the invention.

Referring now to the drawing, the web, band or strip, of fibrous material, which on one side is coated with a layer of agglutinant, is indicated at *a*. An endless conveyor band *b* constructed, for instance, of 35 linen or other suitable material, co-operates with the web of fibrous material, and in operation is continuously drawn over a number of rollers, being maintained continuously 40 stretched by means of tension rollers *c* and *d* in a known manner.

The mica scales or sheets are distributed over the surface of the conveyor band *b* as the latter moves over a supporting platform *e*. This distribution may be effected 45 in various known ways, for example, by blowing the mica scales on to the band by means of a blower, by distributing the scales by hand, or by shaking, by letting the mica scales fall in a shower from a suitable 50 height, or in any other suitable manner.

When the conveyor band *b* covered on its outer side with the mica scales passes under a pressure exerting roller *f* the scales 55 come in contact with the layer of agglutinant on the web of fibrous material *a*, and by

means of the roller *f* and the tension in the conveyor band *b*, are pressed on to the fibrous material.

The pressure roller *f* is heated to a greater 60 or less extent and will require to be highly heated when using a solid agglutinant which is softened by the heating action of the roller, and thus melted on to the fibrous material, so as to permit the cementing of the 65 mica scales transferred from the conveyor band to the fibrous material under the tension of the conveyor band. The agglutinant, however may also be applied to the fibrous material in a fluid condition, and if 70 this be effected by a special machine, the roller *f* must give off sufficient heat to soften the agglutinant to a binding condition. It is moreover, also possible to apply the agglutinant in a liquid condition directly to 75 the fibrous material before its contact with the conveyor band, in which case only so much heat must be given off by the roller *f* as is necessary to drive off moisture and the solvent of the agglutinant. In all cases the 80 pressure roller *f* serves also as guiding member for the agglutinating material or web *a* to preheat same and to thus prepare its agglutinant before it comes in contact with the mica covered band *b*, for securing the 85 agglutinating effect when the two webs *a*, *b* join together at the pressure surface of the roller, where combined pressure and heat act to finally melt the agglutinant and to 90 cement the mica scales on the fibrous material *a*.

After passing the pressure or mica transferring point the conveyor band and the web of fibrous material travel together at the same speed over any desired number of guide 95 rollers and separate from one another after leaving the roller *g*.

At this point, the conveyor band *b* continues its endless course, while the web of fibrous material *a* coated with mica is 100 wound on to a drum *h*, at the same speed as the uncoated material is unwound from the drum *i*.

The mica need not be distributed uniformly over the conveyor band, but it should 105 be observed that the band upon coming into contact with the web of fibrous material should everywhere be covered with at least one layer of mica. As only the mica scales nearest to the agglutinant adhere to the 110 web of fibrous material there is an excess of mica conveyed to the roller *g*, this excess

of mica being released at this point and owing to its own weight falling into a collector *k*.

The removal of the excess of mica may 5 also be effected by means of a rotary shaking device *m* of known type.

The pressure roller *f* may be arranged to be raised from the conveyor band *b* by means of a known lever operated eccentric device *n*.

10 What I claim is:

An apparatus for the manufacture of mica-coated fibrous material for electric insulating purposes, comprising an endless conveyor band with mica scales freely dis-

tributed thereon, tensioning means for said conveyor band, means to supply an agglutinating web of fibrous material and a combined pressure and heating roller arranged to serve first as guiding and preheating member for said agglutinating web and then 20 to apply and press, while heating, said agglutinating web of fibrous material upon the mica carrying conveyor band substantially as and for the purpose described.

In witness whereof I have hereunto signed 25 my name this 30th day of June, 1924.

EMIL HAEFELY.
